UNITED STATES PATENT OFFICE.

GEORGE S. WETTRICH, OF PONTIAC, MICHIGAN.

CALIPERS.

Application filed August 5, 1925. Serial No. 48,249.

This invention relates to calipers and the objects of my invention are to furnish a caliper with a gauging device in the form of an indicator, and to furnish the caliper with 5 means for preventing the indicator from being excessively actuated when the caliper is not in engagement with a piece of work.

Other objects of my invention are to provide a caliper with interchangeable contour

10 jaws which will afford a plurality of gauging points for various kinds of work, and to furnish a caliper of the plier type with an adjustable tension device for holding the jaws of the caliper closed on a piece of work.

15 Further objects of my invention are to provide a caliper having opposed handles with one of the handles constituting a support for an indicator or gauge, and the other handle serving as an actuating medium for 20 the indicator, and to accomplish this and other results by a strong, durable and inexpensive device.

25 My invention will be hereinafter specifically described and then claimed, and reference will now be had to the drawing, wherein

Figure 1 is a side elevation of the caliper; Fig. 2 is a plan of the same, and

Fig. 3 is an end view.

30 In the drawing, the reference numerals 1 and 2 denote plier shaped handles having substantially parallel spaced apart hand grip portions that may be knurled or otherwise roughened so that a firm hand grip 35 may be had for manipulating the caliper. One end of the handle 1 has an apertured ear 3 loosely fitting between a set of apertured ears 4 of the handle 2 and all of said ears are pivotally connected together by a 40 rivet or pin 5. The apertured ears 3 and 4 are formed with arcuated jaw members 6 and 7 having the outer ends thereof apertured, as at 8 for countersunk screws 9 employed for holding jaw blocks 10 and 11 in 45 opposing relation on the jaw members 6 and 7 respectively. The jaw block 11 provides a point contact 12 for a piece of work and the jaw block 11 has two or more contacts 13 for a piece of work, thus providing a

50 three or more point contact between the jaw members 6 and 7 for a piece of work placed in the caliper. The jaw blocks 10 and 11 are interchangeable and blocks of various sizes and configurations may be used in accordance with a piece of work to be measured.

The jaw member 7 is provided with a work stop 14 carried by a slotted plate 15 adjustably secured to one side of the jaw member 7 by a screw 16 or other holding means. This work stop may be positioned to correctly define the location of a piece of work between the jaw members 6 and 7, so that the jaw blocks 10 and 11 may properly engage the piece of work.

Attached to the inner wall of the handle 2, adjacent the apertured ears 4 is a tension device in the form of a flat spring 17 made in two parts with the parts adjustably connected together by a nut equipped screw 18. 60 The parts of the spring may be adjusted to increase or decrease the over-all longitudinal dimension of the tension device and one end of the spring is attached to the handle 2, as at 19, while the opposite end of the 70 spring is curved, as at 20, to bear against the handle 1 and hold the handles 1 and 2 spread apart with the jaw blocks 10 and 11 closed on a piece of work.

The caliper handle 2 has a flat extension 80 21 provided with a slot 22 and extending through said slot is the L-shaped extension 23 of the caliper handle 1. By this arrangement the extensions 21 and 23 have the extremities thereof in proximity to each other 85 and approximately parallel.

On the flat extension 21 is a lug 24 and attached thereto by a set screw 25 is a clamping member 26 supporting the stem 27 of a gauge 28, said gauge being preferably an 90 indicator adapted to be actuated by a pin 29. The pin extends behind the flat extension 21 into engagement with the extension 23 and said extension is also engaged by an adjustable stop 30 carried by the flat extension 21 95 and adapted to be set and held by a jam nut 31. The stop 30 constitutes means for preventing an excessive action of the extension 23 against the indicator pin 29, thus avoiding possible injury to the indicator 100 when not in use.

Since interchangeable jaw blocks are used in connection with the caliper, it may become necessary to adjust the spring 17, the position of the indicator 28, and the stop 30. 105 All of these adjustments are easily performed and the caliper can be readily manipulated in one hand to ascertain a desired exterior dimension. It is apparent that the caliper can be manipulated somewhat similar to a pair of pliers and when placed in engagement with a piece of work the gauge 110

at the inner ends of the handles will determine an accurate measurement in connection with the piece of work. I attach considerable importance to the location of the gauge at the free or inner ends of the handles, since the gauge is of the dial type having its ends substantially at a right angle to the hand grip portions of said handles. By the gauge being on the extension 21 of the handle 2 and of less height than the length of the extension 23, there is clearance above the gauge for an arm gripping the calipers. In other words the gauge is in a convenient location that will not interfere with manipulation of the calipers in the usual manner.

It is thought that the utility of my invention will be apparent without further description, and while in the drawing there is illustrated, a preferred embodiment of my caliper, it is to be understood that the structural elements are susceptible to such variations and modifications as fall within the scope of the appended claims.

What I claim is:—

25 1. A caliper comprising pivotally connected handles, a comparatively flat two-part spring between said handles holding said handles normally separated, said spring having its parts connected together so that said 30 spring may be adjusted in its longitudinal

dimension, jaw members carried by said handles, interchangeable jaw blocks attached to said jaw members, and a gauge supported from one of said handles and actuated by the other handle.

35 2. A caliper having handles with one of said handles having a flat extension, and the other handle an L shaped extension extending through said flat extension so that the extremities of said extensions are in proximity to each other, an adjustable gauge supported from said flat extension and adapted to be actuated by said L extension, and interchangeable jaw blocks supported from said handles.

40 3. A caliper comprising handles having substantially parallel spaced apart hand grip portions, jaws carried by said handles adapted for engagement with a piece of work, a dial type indicator adjustably supported 45 from one of said handles and having its dial axis substantially at a right angle to the hand grip portions of said handles, and adapted to be actuated by the other handle, and means under said indicator and on the 50 indicator carrying handle adapted to prevent an excessive actuation of said indicator.

55 In testimony whereof I affix my signature.

GEORGE S. WETTRICH.
